UNITED STATES PATENT OFFICE.

WILLIAM A. MCCOLLOUGH, OF WEBSTER CITY, IOWA, ASSIGNOR TO W. A. MCCOLLOUGH & SONS, INC., OF WEBSTER CITY, IOWA, A CORPORATION OF IOWA.

CHICK FEEDER.

1,415,376.

Specification of Letters Patent.

Patented May 9, 1922.

Application filed April 11, 1921. Serial No. 460,234.

To all whom it may concern:

Be it known that I, WILLIAM A. MCCOLLOUGH, a citizen of the United States of America, and resident of Webster City, 5 Hamilton County, Iowa, have invented a new and useful Chick Feeder, of which the following is a specification.

The object of this invention is to provide an improved construction for a device for 10 supplying dry feed to chicks and the like.

A further object of this invention is to provide an improved chick feeder which is simple and durable and capable of being constructed economically as to material and 15 labor.

My invention consists in the construction, arrangement and combination of elements hereinafter set forth, pointed out in my claims and illustrated by the accompanying 20 drawing, in which—

Figure 1 is a perspective view illustrating my improved device. Figure 2 is a cross-section on an enlarged scale.

In the construction of the device as shown 25 the numerals 10, 11 designate end walls rectangular in shape and each provided with in-turned flanges 12 at its side margins arranged vertically in planes at right angles to the planes of said walls. A single sheet of metal 30 is bent and shaped to form a bottom 13, low side walls 14, 15 rising perpendicularly from side margins of said bottom, and ledges 16, 17 extending inwardly and upwardly from upper margins of said side walls and spaced 35 above and inclined relative to said bottom. The ledges 16, 17 are formed with integral upturned flanges 18, 19 respectively at their inner margins and substantially at right angles thereto. Inclined hopper walls 20, 21 are 40 provided and are fixed at their lower margins to the flanges 18, 19 respectively and extend upwardly, and outwardly relative to the median line of the device, substantially at right angles to the ledges 16, 17, and extend 45 to the vertical plane of the side walls 14, 15, terminating in outturned horizontal flanges 22, 23 projecting across said vertical planes. The bottom 13, side walls 14, 15, ledges 16, 17 and hopper walls 20, 21 are coextensive in 50 length, and the end walls 10, 11 are fixed to end margins thereof, the flanges 12 of said end walls overlapping end portions of said side walls and extending beneath and supporting at their ends the horizontal flanges 55 22, 23 of said hopper walls.

The ledges 16, 17 and hopper walls 20, 21 are suitably spaced apart at their inner margins and the space between them may be divided by a longitudinally extending partition or deflector 24 resting on and secured to the bottom 13. The deflector 24 preferably has sloping sides and may well be formed of a sheet of metal bent to V shape in cross-section and flanged for securing it to said bottom. The partition or deflector 24 does not extend the entire height of the device but does extend above the horizontal plane of the upper margins of the ledges 16, 17.

Each of the ledges 16, 17 is formed with a plurality of spaced feeding apertures 25 and the height of the side walls 14, 15 and width and inclination of said ledges are such that chickens or other small fowls may readily reach said apertures when standing on a support on which the bottom 13 rests.

A cover 26 is formed of a rectangular sheet of metal of greater width than the bottom and end walls and is formed at its side margins with hooked or recurved flanges 27, 28 adapted to engage, for longitudinal sliding 80 movement, the horizontal flanges 22, 23 of the hopper walls.

If desired one or more transverse partitions 29 may be mounted in the device between and secured to the side and hopper walls, to separate different kinds of feed which may be used.

Particular attention is called to the method of forming the bottom, low side walls and ledges from a single sheet of material, and for mounting the hopper walls relative to 90 said ledges.

The device so formed is simple of manufacture, economical in the use of material, and is exceedingly convenient for the purpose 95 for which it is designed.

I claim as my invention—

1. A poultry feeder, comprising a bottom, vertical side walls rising therefrom, ledges extending inwardly and upwardly from said side walls, said ledges being formed with upturned flanges at their inner margins, and formed with feeding apertures, hopper walls fixed to and extending upwardly and outwardly from the flanges of said ledges, and end walls mounted against end portions of said bottom, side walls, ledges and hopper walls.

2. A poultry feeder, comprising a bottom, side walls rising therefrom, ledges extend-

ing inwardly and upwardly from said side walls, said bottom, side walls and ledges being integrally formed from a single sheet of metal, said ledges being formed with upturned flanges at their inner margins and also being formed with feeding apertures, hopper walls fixed to said flanges and extending upwardly and outwardly from said

ledges, and end walls mounted against the end margins of said bottom, side walls, ledges and hopper walls.

Signed at Webster City, in the county of Hamilton, and State of Iowa, this 26th day of March, 1921.

WILLIAM A. McCOLLOUGH.
